SHIRT COLLAR SUPPORT

Caesar A. Calder, Verona, N. J.

Application March 16, 1948, Serial No. 15,082

1 Claim. (Cl. 223—83)

1

This invention relates to a shirt collar support. In recent years there has been an increased use of men's shirts which comprise attached soft collars and which collars are worn with no starch or very little starch in them. Such collars have very little inherent stiffness and present a problem in packaging such shirts, either in newly manufactured form or in laundered form. Previously known supports which are more particularly adapted for use with shirts having starched or inherently stiffened collars, have been found unsatisfactory when used with the starchless or limp type of collar.

Accordingly it is an object of this invention to provide a shirt collar support which is particularly adapted to be used in supporting soft, starchless shirt collars and shaping such collars to present a pleasing appearance when packaged, such supports being also adapted for use with shirts having starched or otherwise stiffened collars.

Another object of this invention is to provide a shirt collar support comprising an elongated semi-stiff cardboard blank formed at opposite ends thereof with portions adapted to become interengaged, said blank being adapted to be bent to bring said opposite end portions into engagement with each other thus forming said blank into a structure of predetermined peripheral shape, said support being adapted to be inserted into contact with the collar of the shirt and to cause the collar to assume said predetermined shape.

A further object of this invention is to provide a shirt collar support which comprises an elongated strip of cardboard adapted to be bent to bring opposite end portions thereof into engagement, said strip being formed with spaced transverse bend lines which are adapted to determine the peripheral shape of the bent strip, whereby said support when disposed in contact with the collar of a shirt for supporting the same, will suitably shape said shirt collar.

Still another object of this invention is to provide a shirt collar support which comprises an elongated strip of cardboard adapted to have its opposite end portions brought into engagement with each other, one of said end portions being formed with a longitudinal slot, the other of said end portions being formed with a head adapted to be passed through the slot to bring a neck portion in engagement with the edges of the slot, said slotted portion being formed with means permitting the neck portion to move in one direction relative to said slotted portion into any one

2

of a plurality of positions, and preventing movement in the opposite direction, thereby fixing said neck portion in one of said selected positions, thus adjustably determining the peripheral dimension of said support.

Yet another object of this invention is to provide a shirt collar support comprising an elongated cardboard strip formed with a longitudinal slot at one end thereof, the bottom edge 10 thereof being formed with upstanding saw tooth projections, and a head at the other end thereof, said strip being formed with spaced groups of transverse bend lines on portions intermediate the ends of said strip, the ends of said strip being 15 adapted to be brought together, the head portion being adapted to be inserted into the said slot at the inner end of said strip, said head portion then being adapted to be moved in said slot over said projections towards the outer end 20 of said slot, said head portion being adapted to be fixed in any one of a plurality of positions relative to the slotted portion of said strip by means of said projections, said projections being adapted to prevent movement of said head portion 25 towards the inner end of said slot, said support being adapted to have at least portions of its outer peripheral surface disposed in contact with the inner surfaces of a shirt collar, with the head portion of said strip in an initial position 30 adjacent the inner end of the slot in said strip, said head then being adapted to be moved towards the outer end of said slot to enlarge the peripheral extent of said support until its outer surface substantially coincides with the inner 35 surface of said collar, the said bend lines on said strip being adapted to shape said support and thereby shape the collar supported by said support.

Yet another object of this invention is to provide an improved shirt collar support which is inexpensive to manufacture, is readily manipulated in its utilization as a shirt collar support, is adapted for use with shirts of various collar sizes, and is practical and efficient to a high degree in use.

Other objects of this invention will in part be obvious and in part hereinafter pointed out.

The invention accordingly consists in the features of construction, combinations of elements, and arrangements of parts, which will be exemplified in the construction hereinafter described, and of which the scope of invention will be indicated in the following claim.

55 In the accompanying drawings in which is

shown various illustrative embodiments of this invention:

Fig. 1 is a longitudinal front view of a shirt collar support embodying the invention and shown in blank form;

Fig. 2 is a longitudinal rear view thereof;

Fig. 3 is a partial elevational view showing the interengagement of end portions of the blank shown in Fig. 1 with parts broken away and parts in section;

Fig. 4 is a top plan view of the blank shown in Fig. 1 with the opposite ends thereof in engagement;

Fig. 5 is a top plan view of a shirt collar having inserted therein a shirt collar support embodying the invention, with the support in its contracted position, and

Fig. 6 is a top plan view similar to that shown in Fig. 5 and illustrating the support in its expanded position.

Referring now in detail to the drawing, 10 designates an elongated substantially rectangular blank for forming the shirt collar support embodying the invention. Such a blank may be in the form of a strip 11 of cardboard or other suitable semi-stiff material and comprises a front face 12 and a rear face 13. The strip 11 further comprises a top edge 14, a parallel bottom edge 15, and parallel end edges 16, 17, at opposite ends thereof.

The strip is formed with a longitudinally extending rectangular shaped slot 20 disposed adjacent end edge 16. The slot 20 is defined by a top edge 21 parallel to top and bottom edges 14, 15, a bottom edge 22 and opposite parallel end edges 23, 24, which are parallel to end edges 16, the edge 24 being spaced inwardly of edge 16. The edge 22 comprises a plurality of successive upstanding ratchet teeth projections 25 which include vertical upstanding edges 26 and edges 27 inclined upwardly and outwardly to the upper end of edges 26. The inclination of edges 27 is directed towards edge 24 of the slot.

The end of the strip 11 adjacent edge 17 is formed with a curved edge 30 with a neck 31 extending outwardly of a central portion thereof. A headed tongue portion 32 extends from neck 31 and comprises oppositely disposed curved edges 33, 34 which extend to the edge 17. As shown in Figs. 1 and 2, the distance between edges 33, 34 of the tongue 32 is less than the distance between edges 14, 15 of the strip 11.

The strip 11 is provided on its face 12 with a plurality of groups of transverse indented score lines. One group 35 is disposed adjacent the edge 23 of slot 20. Another group 36 is disposed in spaced relation to edge 30. A third group 37 is disposed intermediate groups 35 and 36. A pair of score lines 38 are disposed transversely of the slot 20, adjacent edge 24 thereof. An individual score line 39 is disposed between the edge 30 and the group of score lines 38. Also, the neck portion 31 is provided on the face 13 at either end thereof, with parallel, transverse indented bend lines 31a, 31b for the purpose hereinafter appearing.

The strip 11 which is in a normally flat condition is adapted to be bent into a looped shape substantially as shown in Fig. 4. To this end the headed tongue 32 is brought towards the slotted portion of the strip and the tongue is inserted through the slot by twisting the tongue axially, sufficient to permit the tongue to pass through the slot 20. The tongue is then restored to its normal position. Preferably, the

tongue is inserted into the slot 20 adjacent edge 23. As a consequence, the lower edge of the neck 31 will become engaged with one of the projections 25 adjacent the edge 23. The lower neck edge is thus disposed between a vertical edge 26 and the adjacent inclined edge 27. The upper edge of the neck will contact edge 21 of the slot. The tongue 32 is then bent back on the neck portion 31 along bend lines 31a, 31b, towards the end 16, bringing it into contact with the face 13 of the strip. The strip 11 is thus caused to be bent along the groups of indented bend lines 35, 36, 37 to produce a looped member having convexly curved portions 40, 41, 42. The strip 11 with its ends thus interengaged, as shown in Fig. 4, is ready to be inserted into the collar portion 50 of newly manufactured or freshly laundered shirts 51, to provide supports therefor. The collar 50 which is of the attached type, may be unstarched or have very little starch therein. Such collars, although quite fashionable are difficult to support due to lack of stiffness.

The collar 50 comprises the usual outer layer 52 with tabs 53 at the front thereof, a roll top edge 54 and an inner layer 55. The inner layer 55 is provided at the front with overlapping buttoned ends 56.

The collar support shown in Fig. 4 is inserted into the collar 50 so that the face 13 of the support is disposed opposite the inner layer 55 of the collar as shown in Fig. 5. With the headed tongue 32 in the slot 20 and positioned adjacent edge 23, the looped structure is of minimum peripheral dimension and is designed to be somewhat less than the smaller sizes of shirt collars. The support is then expanded so as to bring the surface 13 thereof into contact with the inner surface of the inner layer 55 of the collar as shown in Fig. 6. This may be readily accomplished by spreading the opposite portions of the looped support away from each other. This spreading action is accomplished by movement of the neck 31 and headed tongue 32 within the slot 20 in the direction of the edge 24 of said slot, the neck slipping over the successive inclined edges 27 of the ratchet teeth projections 25. When the support conforms in its peripheral dimensions to the size of the collar, it will retain such dimensions by reason of the projection 25 which permits movement of the neck and tongue towards the edge 24 of the slot but prevents movement towards edge 23 of the slot.

Since the support is preshaped by reason of the spaced groups of indented bend lines, the collar 50 which is more flexible than the support, will tend to assume the shape of the support. As shown in Figs. 5 and 6 the intermediate curved portion 41 on the support is disposed opposite the button portion 56 of the collar. The other curved portions 40 and 42 on the support will be disposed at opposite sides of the collar and will thus produce a shaped collar of pleasing and attractive appearance.

It will be apparent that the headed tongue 32 will be disposed between the face 13 of the support and the inner layer 55 of the collar at the back thereof. Since the end portion of the looped strip 11 adjacent edge 16 will have a tendency to move away from the interengaged opposite end portion due to the tendency of the strip to restore itself to its original flat condition, the support will frictionally grip the inner surface of the collar 50 and will stay in its proper position.

The bend lines 38 and 39 provide means for

imparting additional curvature to the strip 11.

It is understood that the shirt collar support embodying the invention may be used with shirts having starched as well as unstarched collars, in each case the support being adapted to present the collar of the shirt in a pleasing manner when packaged.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, what I claim as new and desire to protect by Letters Patent of the United States, is:

A shirt collar support comprising an elongated cardboard strip, said strip comprising parallel top and bottom edges, said strip being formed with a longitudinal slot adjacent one end thereof, the other end thereof comprising a headed tongue

and a neck portion connecting said tongue and the body portion of said strip, said tongue being adapted to be inserted into said slot with said neck portion extending transversely of said slot, one longitudinal edge of said slot being formed with ratchet teeth adapted to engage an edge of said neck, each of said teeth having an edge perpendicular to said parallel edges and an edge inclined toward the first end of said strip and toward said top edge, the width of the neck being such that the other edge of the neck is contacted by the other longitudinal edge of the slot.
